(57) **CLAIM**

The ornamental design for a wheelchair base curved end panel, as shown and described.

DESCRIPTION

FIG. 1 is a perspective view of a wheelchair base having a curved end panel according to the present design disposed thereon;

The broken lines shown in FIG. 1 are for illustrative purposes only and are provided to illustrate the present design in its intended environment; the broken lines form no part of the claimed design.

FIG. 2 is a perspective view of the wheelchair curved end panel illustrated in FIG. 1;

FIG. 3 is a top plan view of the wheelchair curved end panel illustrated in FIG. 1;

FIG. 4 is a front plan view of the wheelchair curved end panel illustrated in FIG. 1;

FIG. 5 is a right side end elevation view of the wheelchair curved end panel illustrated in FIG. 1; and,

FIG. 6 is a bottom plan view of the wheelchair curved end panel illustrated in FIG. 1.

The broken lines shown in FIGS. 2-6 are for illustrative purposes only and form no part of the claimed design.
